UNITED STATES PATENT OFFICE.

JOHN W. GORHAM, OF ESCONDIDO, CALIFORNIA.

FOOTWEAR-LACING MEANS.

Application filed March 20, 1922. Serial No. 545,038.

To all whom it may concern:

Be it known that I, JOHN W. GORHAM, a citizen of the United States, residing at Escondido, in the county of San Diego and State of California, have invented a certain new and useful Footwear-Lacing Means, of which the following is a specification.

My invention relates to footwear lacing means and the objects of my invention are: first, to provide a means of this class in which the lace supports are so positioned that a minimum of friction is produced in drawing the lace through said supports; second, to provide a means of this class in which it is not necessary to pull the ends of the lace through or out of the eyes or hooks of the footwear in order to put said footwear on or take it off; third, to provide a means of this class which reduces to a minimum the length of time required for the lacing of footwear; fourth, to provide a means of this class which renders the shoe flexible and therefore will provide perfect accommodation to the shape and movements of the foot; fifth, to provide a means of this class in which the eyes and hooks can be readily replaced in a shoe in case of wear or breakage; sixth, to provide a lace which can not readily be pulled out of the eyes; seventh, to provide a footwear lacing means which is novelly constructed, and eighth, to provide a means of this class which is simple and economical of construction, durable, applicable to all footwear and which will not readily deteriorate or get out of order.

With these and other objects in view as will appear hereinafter my invention consists of certain novel features of construction, combination and arrangement of parts and portions as will be hereinafter described in detail and particularly set forth in the appended claims reference being had to the accompanying drawings and to the characters of reference thereon which form a part of this application in which:

Figure 1 is a perspective view of a shoe, taken in front of and above the same, showing the new lacing means; Fig. 2 is an enlarged fragmentary portion of the shoe upper near and at one front edge thereof partly in section to facilitate the illustration of the eyes secured therein at the front edge thereof; Fig. 3 is a sectional view through 3—3 of Fig. 2; Fig. 4 is another fragmentary portion of a shoe upper near

the top side and at one front edge thereof partly in section to facilitate the illustration of the hook secured therein at the front edge thereof; and Fig. 5 is a sectional view taken through 5—5 of Fig. 4.

Like characters of reference refer to similar parts and portions throughout the several views of the drawings.

The shoe upper 1, eye 2, hook 3 and the lace 4 constitute the principal parts and portions of my lacing means.

The shoe upper 1 is provided at the front open edges 1^a with turned under portions 1^b and stitching 5 securing the same in such position. Said shoe upper is further provided at the front open edges with perforations 1^c adapted to receive therethrough the eye and hook portions 2^a and 3^a of the eye and hook members 2 and 3 respectively. Said eye members 2 are preferably made with slightly flattened eye portions 2^a as shown in Fig. 3 of the drawings and are further provided with outwardly extended portions 2^b at either end of said eye portions adapted to retain said eye members in the holes 1^c provided for the same at the edges of the shoe upper. Said eye members are prevented from slipping or being forced inwardly by the stitching 5 securing said turned under portion 1^b to the shoe upper proper. The hook members 3 are similarly provided with hook portions 3^a and extended portions 3^b on either side of said hook portion adapted to secure said hook members in similar holes provided for the same at the front edges of the shoe upper. Said hook members are further provided at the ends of said extended portions with projected portions 3^c secured at right angles thereto and extending inwardly therefrom adapted to prevent said hook member from turning in said shoe upper. The laces 4 may be made of any flexible material desired and of any desired cross section but are provided at their ends with loops 4^a or other means so that they may be readily introduced or pulled through the eyes 2^a but cannot readily be pulled out or back through said eyes.

It will be here noted that the eyes are so shaped and positioned that the lace in passing through said eyes is always parallel with the edge of the shoe upper and not crosswise as is the conventional eyelet, thus reducing the friction to a minimum and

that the eyes and hooks extend forward of the edges of the shoe upper so that the laces, when drawn, are nearly parallel.

It will be noted that my lacing means 5 may be composed of eye members extending the full length of the front edge of the shoe upper as described and shown or may consist of hook members 3 extending the full length thereof or may consist of a combination 10 of eye members at one portion of the front edges of the shoe upper and hook members at the other portions thereof.

Although I have shown and described a particular construction, combination and 15 arrangement of parts and portions I do not wish to be limited to this particular construction, combination and arrangement but desire to include in the scope of my invention the construction, combination and 20 arrangement substantially as set forth in the appended claims:

Having thus described my invention what I claim as new and desire to secure by Letters Patent is:

25 1. In a means of the class described, a footwear upper provided with overturned front edges with perforations in the edges thereof, lace retaining members provided with lace retaining portions, and extended

portions substantially at right angles with the axes of said lace retaining portions, secured in said footwear upper at the front edges thereof, said lace retaining members being also provided with other inwardly extending portions at right angles with said other extended portions for preventing said lace retaining members from turning, the lace retaining portions of said members protruding through said perforations.

2. A means of the class described, including a footwear upper provided with overturned front edges with perforations in the edges thereof, hook members provided with hook portions and extended portions substantially at right angles with said hook portions, secured in said footwear upper at the front edges thereof, the hook portions of said hook members protruding through said perforations, the extended portions of said hook members being provided at their ends with other inwardly extending portions substantially at right angles with said first mentioned extended portions.

In testimony whereof, I have hereunto set my hand at San Diego, California this 10th day of March 1922.

JOHN W. GORHAM.
